UNITED STATES PATENT OFFICE.

KARL STEINBECKER, OF CHARLOTTENBURG, GERMANY, ASSIGNOR TO GENERAL ELECTRIC COMPANY, A CORPORATION OF NEW YORK.

METALLIC-DIAPHRAGM PUMP.

1,085,306.

Specification of Letters Patent.

Patented Jan. 27, 1914.

Application filed September 7, 1911. Serial No. 642,013.

To all whom it may concern:

Be it known that I, KARL STEINBECKER, a subject of the King of Prussia, residing at Charlottenburg, Germany, have invented 5 certain new and useful Improvements in Metallic-Diaphragm Pumps, of which the following is a specification.

This invention relates to pumps for forcing very small quantities of fluid—as to 10 the fuel injectors or atomizers of internal combustion engines—in which the suction and delivery are effected by the fluctuations of a metallic diaphragm. Heretofore in diaphragm pumps the diaphragm has been 15 flat or only slightly arched, so that even with slight flexions thereof a comparatively large forcing power was obtained, and regularity in delivery was well-nigh impossible. Pumps have also been made with leather 20 bellows, but these are not always reliable where exact similarity in the increments of fluid delivered for a given length of stroke is absolutely necessary, as for instance in the feeding of the combustible in oil engines. 25 My invention is especially designed for this particular service, and permits the use of a comparatively long regulable stroke even though but very small amounts of liquid are to be forced. It further insures 30 that even after quite long service the predetermined exact amount of fluid will be always delivered for a given length of stroke. To accomplish this desirable result, I employ a bellows-fold diaphragm made of thin 35 resilient metal, which is compressed by a lever actuated at regular intervals by the oil engine. The length of the stroke can be regulated by varying the throw of the lever in any one of several ways. The lever moves 40 the diaphragm in one direction only, to effect the forcing of the fluid; the return suction stroke being due to the elasticity of the metal of which the diaphragm is composed. 45 The accompanying drawing is a sectional elevation of a pump embodying my improvements.

In the pump casing 1 are inserted the suction valve 2 and the discharge valve 3 which 50 are pressed upon their seats by the springs 4. The supply pipe 5 is attached to a shoul-dered plug 6 inserted in a socket in the hous- 55 ing 7 for the valve 2, and pressed tightly

on its seat by a union 8. A similar coupling 9, for the discharge pipe 10 is secured by a 55 gland 11. Communicating with one end of the pump casing is the bellows-like dia-phragm 12, composed of resilient metal, and having a plurality of folds of comparatively small diameter so that the structure is 60 rather long and narrow. The closed end of the diaphragm rests upon one end of a lever 13 suitably fulcrumed on the pivot 14. The opposite end of said lever stands in line with a regularly reciprocating part of the 65 engine, such for instance as the plunger rod 15. When said rod is at one end of its stroke, it is at a sufficient distance from the lever to permit the latter to be adjusted for the purpose of varying its throw and conse- 70 quently regulating the quantity of fluid ejected at each stroke of the pump. While any suitable adjusting device may be used, I prefer to place an eccentric 16 under the arm 17 of the lever, and provide an arm 18 75 on the shaft of said eccentric whereby the latter can be turned, either by hand or by the governor of the engine. When the ec- centric is adjusted by hand, it will be held fast in the desired position by suitable 80 means.

The operation is as follows: The eccentric 16 is set to afford more or less lost motion between the plunger 15 and the lever 13, so that only a predetermined portion of the 85 constant stroke of said plunger will be effec-tive to compress the bellows-like dia-phragm 12. At each such compression, an exact quantity of fluid will be forced out of the pump casing 1 through the discharge valve 90 3 and pipe 10. When the plunger recedes from the lever the resilience of the dia-phragm 12 forces the lever back to its origi-nal position and at the same time sucks a 95 fresh supply of fluid through the valve 2 into the pump casing. The quantity of fluid sucked in and discharged at each stroke of the pump can be varied by adjusting the position of the eccentric 16, assuming an un-varying stroke of the plunger 15. 100

In accordance with the provisions of the patent statutes, I have described the prin-ciple of operation of my invention, together with the apparatus which I now consider to represent the best embodiment thereof; 105 but I desire to have it understood that the

apparatus shown is only illustrative, and that the invention can be carried out by other means.

What I claim as new and desire to secure 5 by Letters Patent of the United States, is,—

1. A pump for delivering small quantities of fluid, comprising a casing, suction and discharge valves, a long and narrow bellows-like diaphragm of resilient metal connected with said casing and tightly closed at one end, a lever bearing loosely against the closed end of said diaphragm, and a reciprocating member having a constant stroke and acting upon the free end of said lever.
- 15 2. A pump for delivering small quantities of fluid, comprising a casing, suction and discharge valves, a bellows-like metallic diaphragm connected with said casing, a lever bearing against the closed end of said diaphragm, means for regulating the stroke of said lever, and a constant-stroke member acting on the free end of said lever.
- 20 3. A pump for delivering small quantities of fluid, comprising a casing, suction and discharge valves, a bellows-like diaphragm

of resilient metal connected with one end of said casing, a lever bearing against the closed end of said diaphragm, an eccentric for regulating the throw of said lever, and a reciprocating plunger of constant stroke co- 30 operating with said lever.

4. In a pump, the combination of a casing, suction and discharge valves mounted therein, a bellows-like metallic diaphragm that is connected to and supported by the 35 casing, a lever arranged to be vibrated on its pivot to compress the diaphragm and force fluid through the discharge valve, a device having a constant length of stroke for actuating the lever, and a regulator for 40 the pump which limits the expansion movement of the diaphragm and the arc of movement of the lever.

In witness whereof, I have hereunto set my hand.

KARL STEINBECKER.
